MOLD FOR CENTRIFUGAL CASTING

Shelley M. Stoody and Ralph L. Abos, Whittier,
Calif., assignors to Stoody Company, Whittier,
Calif., a corporation of California

Application December 24, 1941, Serial No. 424,371

1 Claim. (Cl. 22—134)

This invention relates to a means and method of centrifugally casting.

An object of the invention is to provide a novel mold construction for centrifugally casting metals and like materials which will ensure that the casting produced will be of a fine-grained, homogeneous metal characterized by the absence of dirt or loose particles of mold material and by the absence of oxides or nitrides and by the absence of blow holes.

In the normal method of centrifugally casting metals it has been customary to construct the mold having a plurality of radial passages leading from a central gate to mold cavities. In pouring the molten metal into the central gate it is subjected to centrifugal action and is drawn outwardly through the passages to the mold cavities. The initial metal that is poured into the mold is chilled to some extent on encountering the relatively cold walls or surfaces of the gate and passages. The initial metal is of course subjected to an outward acceleration as it is subjected to the centrifugal action. Any dirt or loose particles of mold material in the passages are of course picked up and thrown outwardly by the accelerating initial metal. The initial metal also tends to separate into globules or a spray and under normal circumstances as there is air in the mold this initial metal becomes well oxidized. If the metal is of such a character as to chemically combine with or absorb nitrogen, nitrides may be formed which may be objectionable in certain instances.

In the conventional method of centrifugally casting the radially extending passages lead directly into the mold with the result that dirt, loose particles of mold material, and the oxides or nitrides are all carried into the mold cavity and form a substantial portion of the finished casting. Frequently the radial passages are of considerable volume and the air therein is forced into the mold cavity resulting in blow holes in the casting unless the mold cavity is adequately vented.

The present invention has for its primary object the elimination or bypassing of the initial metal that is subjected to centrifugal action so that this metal does not enter the mold cavity carrying with it dirt or mold material, the oxides or nitrides or included air. Only the trailing metal that follows the initial metal and which is not subjected to such a severe chilling action is caused to enter the mold cavity. This trailing metal is not only relatively free from dirt but also of air and oxides with the result

that a pressure casting is produced of fine-grained homogeneously pure metal.

With the foregoing and other objects in view, which will be made manifest in the following detailed description and specifically pointed out in the appended claim, reference is had to the accompanying drawings for an illustrative embodiment of the invention, wherein:

Fig. 1 is a top plan view of a mold that may be advantageously employed in performing the method embodying the present invention;

Fig. 2 is a vertical section taken substantially upon the line 2—2 upon Fig. 1;

Fig. 3 is a vertical section taken substantially upon the line 3—3 upon Fig. 2;

Fig. 4 is a sectional view through an alternative form of mold embodying the present invention; and

Fig. 5 is a horizontal section taken substantially upon the line 5—5 upon Fig. 4.

Referring to the accompanying drawings wherein similar reference characters designate similar parts throughout, the mold utilized is usually rotated about a vertical axis and may be rotated, such as by an electric motor 10, having a vertical spindle 11 on which is supported a circular carrier 12. Within the carrier there is positioned the parts forming the mold, the upper part or cope being indicated at 13 and the lower part or drag at 14. These are preferably formed of carbon. The parting line or plane between the parts 13 and 14 is indicated at 15. In the upper part or cope 13 there is a central gate 16 which leads to the inner ends of a plurality of outwardly or radially extending passages 17 formed in the upper surface of the lower part or drag 14. Each passage 17 leads to its respective mold cavity. The mold cavities may be provided by tamping mold material 18 in a cylindrical carbon flask 19 that is receivable in a vertical bore or aperture in the cope 13 over each radial passage 17. For purposes of illustration the mold cavity illustrated in Fig. 2 extends from approximately the point 20 to the point 21. Below the point 21 there is a mold entrance 22 that leads from the passage 17 to the mold cavity. This entrance it will be noted is disposed some distance inwardly from the outer end of the passage 17. Above the point 20 there may be one or more vent passages 23. A suitable cover 24 which may be stationary largely encloses the rotating mold.

In casting metal in accordance with the present invention the molten metal is poured into the central gate 16 through which it flows down-

wardly to the inner ends of the radiating passages 17. It is there subjected to centrifugal action. The initial metal that first enters the passages 17 is of course subjected to centrifugal action first and accelerates outwardly through the passages 17 under the influence of the rotating mold. This initial metal picks up and carries with it any dirt or loose material that may be in the passages 17. It frequently divides or separates into a spray and is thrown outwardly to the extreme end of the passages with considerable force. The initial metal is of course usually chilled to a considerable extent by the cold mold. All dirt or chilled metal and objectionable oxides or nitrides are thus carried out to the ends of the passages 17 beyond the entrances 22 of the mold cavities. The trailing metal that follows the initial metal is not subjected to as great a chilling action by the mold due to the fact that the initial metal has already heated it and is not subject to oxidation or nitriding to the same extent as the initial metal. It piles up behind the initial metal and under the continued centrifugal force develops a considerable pressure with the result that the trailing metal is forced upwardly through the entrance 22 into the mold cavity. Air that is present in the mold cavity is of course expelled through the vent 23. In this way only trailing metal which is free of dirt, free of oxides, and free of air is caused to enter the mold cavity resulting in a fine-grained, clean homogeneous casting. When the metal has cooled the parts of the mold are then taken apart or broken open and the casting recovered. The casting is usually broken off at the entrance 22. The metal that remains in the passages 17 may be either regarded as waste or may be melted a second time in which case the dirt and oxides present in the initial metal at the outer ends of the passages 17 usually can be removed from the remelt as slag. In this way it is possible to secure what are in effect pressure castings without having the casting include chilled, dirty or oxidized metal.

In the preferred form of construction the mold cavity is arranged vertically above the radial passages 17 which rotate in a horizontal plane. However, these mold cavities may be arranged below the passages 17 if necessary or desirable. The centrifugal force developed in the metal will ordinarily throw it out in a horizontal direction over the top of the entrance 22 if this entrance is disposed below the passage 17 with the result that the initial metal is carried outwardly beyond the entrance to the mold cavity and retained there allowing only trailing metal to enter the mold cavity which trailing metal is relatively clean.

An alternative method of casting is disclosed in Figs. 4 and 5, wherein the centrifugal molding apparatus comprises a suitable carrier 30 rotated as by a motor 31. The carrier supports in superposed relationship two cast iron blocks 32 and 33 which are separated from each other by a carbon plate 34 in which the radiating passages 35 are formed. The opposed faces of the cast

iron blocks may be flat and straight. The blocks have apertures therethrough indicated at 36 that receive carbon flasks 37 in which carbonaceous molding material 38 has been rammed up about a pattern to form the mold cavity 39. As will be noted the entrances 40 to the mold cavities communicate with the radial passages 35 inwardly of the outer ends of the radial passages. A central gate 41 is formed in the upper block. 5 10 15 20 25 30 35 40 45 50 This form of construction is preferable where the size and shape of the casting to be produced is such as to enable a large number of castings to be cast during a single operation. By arranging the molds above and below their respective radial passages 35, each radial passage will supply the metal to both molds. However, as the radial passages extend outwardly beyond the entrances 40 they form at their outer ends recesses or cavities which receive the initial metal that is apt to be chilled, dirty, and badly oxidized. In this form of construction as before, only the trailing metal enters the mold cavity, and as the trailing metal is relatively clean, a solid, fine-grained, homogeneous casting can be produced. The initial metal that flows outwardly through the radial passages does not flow by gravity into the lower mold cavities but is usually thrown out with sufficient force and acceleration that it flows directly across the lower mold entrances into the outer ends of the radial passages which serve to bypass it from entering the mold cavities. Ordinarily the metal cast will not eat into or burn or dissolve the faces of the cast iron blocks at the top and bottom of the passages. However, should this occur the blocks can be easily machined or planed off so as to cause the parts of the casting apparatus to properly fit together against opposite sides of the carbon plate.

40 While we have referred herein to centrifugally casting metals it will be appreciated that the invention is in no way restricted thereto but may be advantageously employed for casting other substances which will harden when poured into a mold. The present invention lends itself to the making of fine small precision castings requiring very little if any machine work. The present application may be regarded as a continuation in part of an application contemporaneously filed herewith entitled Method of making precision castings, Serial No. 424,370, filed December 24, 1941.

Various changes may be made in the details of construction without departing from the spirit or scope of the invention as defined by the appended claim.

We claim:
60 A mold for centrifugally casting having a central gate into which metal is poured, one or more outwardly extending passages leading therefrom, there being one or more mold cavities in the mold, the entrances to which extend upwardly from their respective passages from points disposed inwardly of the outer ends of the passages.
